UNITED STATES PATENT OFFICE.

LOUIS McCARTHY, OF BOSTON, MASSACHUSETTS, ASSIGNOR TO THE MACALLEN COMPANY, OF BOSTON, MASSACHUSETTS, A CORPORATION OF MASSACHUSETTS.

PRESS PLATEN OR THE LIKE.

Application filed August 30, 1924. Serial No. 735,201.

This invention relates to hollow metal plates or plate-like articles, and especially, although not exclusively, to composite plates or platens for use in hydraulic and similar presses and having interior cavities or passages for the circulation of a heating or cooling fluid, such as steam, oil, or water.

Platens of this type have heretofore usually been made of cast-iron, cored out to form the fluid passages. Such platens are of short life, are brittle and easily broken, will stand only relatively low pressures, are necessarily thick and heavy, are troublesome to handle as well as taking up undue space in the press and, by reason of their mass, heat and cool relatively slowly. Moreover, in the process of casting such platens, difficulty is frequently encountered with floating cores, resulting in thin walls at one face of the platen, thereby further decreasing their durability, as well as interfering with their even heating. Furthermore, in coring such platens, openings are formed by the ends of the cores which openings must be carefully plugged in order to avoid leakage at these points.

In an attempt to avoid certain of these difficulties, it has heretofore been proposed to form a composite plate or platen in two sections which are subsequently riveted together, face to face, by rivets extending all the way through both sections. Such a platen is of somewhat longer life than a cast-iron platen and is thinner and lighter, so as to be handled more easily, take up less space in the press, and heat and cool more quickly. Such a platen cannot, however, be subjected to high internal pressures without opening the riveted joints so as to permit leakage, while the rivet heads interrupt the continuity of the faces of the platen, so as to mar the work, and, if of sufficient number to hold the parts together with any degree of security obstruct the fluid passages within the platen and seriously interfere with the circulation of the heating or cooling fluid.

The present invention has for its primary object to provide a platen which will be free from all of the objectionable features of the types above referred to, which may be composed of steel or any other suitable metal, which is of unitary construction and practically indestructible, which will withstand, without breakage or leakage, substantially any internal or external pressure to which

such a device is likely to be subjected, which is relatively thin and light, and which provides a continuous, unobstructed, tortuous passage for the thorough circulation of the heating or cooling medium and presents a smooth and uninterrupted surface for engagement with the work.

The foregoing and other objects of the invention will best be understood from the following description of a platen made in accordance with the invention and of the several steps by which its manufacture is accomplished. It will be understood, however, that the particular constructions and operations illustrated and described have been chosen for purposes of exemplification merely, and that the invention, as defined by the claim hereunto appended, may be otherwise embodied and practiced without departure from the spirit and scope thereof.

In said drawings:

Fig. 1 is a somewhat conventionalized view of a portion of a hydraulic press in which are used platens of the type to which the invention primarily relates.

Fig. 2 is an inside face view of one of the members or sections of which the complete composite plate or platen is composed.

Fig. 3 is an end view of the plate member shown in Fig. 2.

Figs. 4, 5 and 6 are sections taken substantially on the lines 4-4, 5-5, and 6-6, Fig. 2.

Fig. 7 is a partial side elevation of the plate member shown in Fig. 2.

Fig. 8 is an inside face view of the other plate member or section.

Fig. 9 is an end view of the plate member shown in Fig. 8.

Fig. 10 is a plan view illustrating the assembling of the members or sections shown in Figs. 2 and 8.

Fig. 11 is an end view of the assembled plate member.

Fig. 12 is a transverse section thereof.

Fig. 13 is a fragmentary perspective view illustrating the welding together of the edges of the plate member.

Fig. 14 is an enlarged detail sectional view, taken substantially on the line 14-14, Fig. 10, of the completed platen.

In Fig. 1 is shown somewhat diagrammatically a portion of hydraulic press having a bed or stationary element 20 and a co-operating movable element 21 carried by a

ram 22 and guided by posts 23 rising from the bed 20. Interposed between the elements 20 and 21 are two or more platens 24 between which are placed the sheets or other articles 25 to be operated upon by the press, said platens having interior cavities or passages for the circulation of steam, water or other heating or cooling fluid supplied thereto through branch pipes 26 from a header 27. 10 As shown in Figs. 2 to 14, each platen 24 is composed of two members or sections, including a body member or section 28 (Figs. 2 to 7 and 10 to 14) and a cover member or section 29 (Figs. 8 to 14), said members or 15 sections being formed and assembled into a unitary composite plate structure as herein-after described. The members or sections 28 and 29 are preferably composed of steel, or may be of any other metal suitable to the 20 requirements.

The inner surface of the body member 28, or that surface thereof which, in the completed platen, is disposed toward the cover member 29, is provided with a cavity between the plate members in the form of a continuous tortuous passage 30 preferably composed of a plurality of parallel longitudinal open grooves 31 connected alternately adjacent opposite ends of the plate by 25 connecting grooves 32 and separated by parallel partitions 33 each of which extends from one of the connecting grooves 32 to the opposite end of the plate. The grooves 31 are preferably of an even number, so that 30 both ends of the passage 30 are located adjacent one end of the plate, at which points said plate is formed with tapped openings 34 for the attachment of the branch supply pipes 26. While the passage 30, partitions 33, 40 and openings 34 may be otherwise formed, the surface of the plate member 28 is preferably machined to form the grooves 31 and 32, leaving the partitions 33, and the openings 34 drilled in the end of the plate 45 to communicate with the ends of the passage 30. The surface of the member is further machined to form parallel undercut or dove-tailed ribs 35, said ribs preferably following the partitions 33, being interrupted 50 opposite the connecting grooves 32, but comprising portions 36 at the ends of the members beyond said grooves. The edges of the member 28 are preferably chamfered, as shown at 37, for a purpose presently to 55 be explained.

The inner face of the cover plate 29, or that which, in the finished platen, is disposed toward the body plate 28, is also preferably machined to form a series of parallel 60 undercut grooves 38 complementary to the ribs 35, 36 of the body plate 28, corresponding in number and arrangement thereto, and of a size to receive the same with a close drive fit. The edges of the plate member 65 29 are also chamfered, as shown at 39, to

correspond to the chamfering 37 of the edges of the plate member 28.

The members 28 and 29 formed as above described are then assembled and mechanically interlocked with one another to form 70 the complete platen by driving or forcing the undercut ribs 35, 36 of the body plate member 28 longitudinally into the undercut grooves 38 of the cover plate member 29, as illustrated in Fig. 10, under heavy pressure, preferably in a hydraulic press. The edges of the members 28 and 29 are then welded together throughout their length, preferably by "burning" or fusing a strip of metal 40 (Fig. 13) in the groove formed 80 by the chamfered edges 37 and 39 by means of an oxy-acetylene flange 41 to form a welded joint 42 (Figs. 13 and 14).

When a platen thus produced is put into use, and steam or water admitted to the passage 30, the driven interlocked joints formed by the ribs 35, 36 and grooves 38 quickly rust together, forming a substantially unitary connection at these points in addition to the welded connection at the 90 edges of the plate members. The platen thus becomes a substantially unitary structure which is adapted to withstand extremely high internal as well as external pressures without failure or leakage. By reason of its construction and mode of production the platen can be composed of suitable steel, and is therefore of long life and may be made relatively light and thin, so as to be easily handled and to take up relative small space in the press, nearly doubling the capacity of the latter as compared to a cast-iron platen. Moreover, the thinness of the platen enables it to be heated or cooled quickly and easily, it being observed that the passage 30 extends substantially throughout the length and width of the platen and is continuous from one opening 34 to the other, so that fluid admitted at one of said openings must pass longitudinally throughout the entire 100 length of the passage to the other opening without possibility of leakage from one branch of said passage to another, thereby circulating throughout the entire body of the platen. It will also be observed that the passage 30 is of substantially constant cross-sectional area throughout, being unobstructed by rivets, and that the surfaces of the platen designed for contact with the work 25 are smooth and unbroken throughout. Since the passage 30 is formed as an open groove on one face of the body plate member 28, its position may be accurately determined, so that the thickness of the walls 110 may be made constant and of any desired amount.

While, as above pointed out, the invention is primarily applicable to press platens, it will be obvious that it is by no means limited thereto but might readily be em- 120

ployed in connection with other devices, such, for example, as steam tables, heated molds, etc., and I wish it distinctly understood that such other uses and applications of the invention are fully contemplated in the definition of the latter by the following claim.

Having thus described my invention, I claim:

10 A composite hollow steel plate, primarily intended for use in presses, and composed

of two flat members having between them a continuous, tortuous, fluid passage provided by a plurality of parallel, interrupted partitions, said plate members being positively 15 connected internally by undercut interlocking ribs and grooves, and said plate members being sealed externally by a continuous welded joint.

In testimony whereof I affix my signature.

LOUIS McCARTHY.
